Attest,

UNITED STATES PATENT OFFICE.

HERBERT G. MACKINNEY, OF PROVIDENCE, RHODE ISLAND.

DESIGN FOR JEWELRY.

SPECIFICATION forming part of Design No. 12,735, dated February 7, 1882.

Application filed November 30, 1881. Term of patent 3½ years.

To all whom it may concern:

Be it known that I, HERBERT G. MACKINNEY, a citizen of the United States, residing at the city and county of Providence, State of Rhode Island, have invented and produced a new and original Design for Various Articles of Jewelry—such as charms, breast or other pins, ear-rings, &c.—of which the following is a specification, reference being had to the accompanying drawings, forming part thereof, in which—

Figure 1 represents a breastpin with my proposed design applied thereto; Figs. 2 and 3, different modes of applying the design.

This design consists of a miniature figure, *c*, of a horseshoe form, intended to represent the horseshoe-magnet, and two miniature figures, *b b*, of an old-fashioned barrel-churn.

As shown in Figs. 2 and 3, the positions of

the parts *a* and *b* may be changed, also the mode of attachment to the plate *a*, which forms no part of the design, but is simply the body of the breastpin to which the design is applied, the essential features of the design being the magnets and churn. 20 25

As is evident, the design may be applied to various other articles of jewelry besides the breastpin herein shown and described.

I claim—

The design for articles of manufactured jewelry, consisting of miniature representation of a horseshoe-magnet and churns, applied, substantially as herein shown and described, in connection with the plate or body *a*. 30

HERBERT G. MACKINNEY.

In presence of—

SIMON S. LAPHAM,

JOHN T. BLODGETT.
